UNITED STATES PATENT OFFICE.

JOSEPH S. BECK, OF MEDINA, OHIO.

RAILWAY-SPICE.

No. 843,782.

Specification of Letters Patent.

Patented Feb. 12, 1907.

Application filed November 7, 1906. Serial No. 342,365.

To all whom it may concern:

Be it known that I, JOSEPH S. BECK, a citizen of the United States, residing at Medina, in the county of Medina and State of Ohio, 5 have invented certain new and useful Improvements in Railway-Splices, of which the following is a specification.

My invention relates to improvements in railways, more especially what may be 10 termed "splice-bars" therefor. Its objects are to effectively couple together adjacent rail-sections, to guard against the displacement of such rail-sections in event of the car-wheels in case of derailment stripping off the 15 nuts upon that side of the track, to lock the nuts against accidental jarring off or unscrewing of the nuts, and to accomplish these ends in a simple, economic, and effective manner.

Said invention consists of certain structural features or instrumentalities, substantially as hereinafter fully disclosed, and specifically pointed out by the claims.

In the accompanying drawings, illustrating the preferred embodiment of my invention, Figure 1 is a plan view thereof. Figs. 2 and 3 are opposite side views of the same. Fig. 4 is a cross-section thereof produced in the line of one of the pawl-and-ratchet-equipped bolts. Figs. 5 and 6 are disassembled perspective views of a spring locking dog or pawl and a ratchet-nut, respectively.

In carrying out my invention I suitably provide splice-bars 1, one for each side of the rail-sections 2, oppositely to the joint of the latter, as usual. Said splice-bars are connected together and held firmly against the lateral surfaces of the rail-sections by nut-equipped bolts 3, having angular surfaces 4 where they pass through one splice-bar, the 35 latter accordingly having a corresponding aperture 5 for its reception to prevent the accidental turning of the bolts, as will be readily appreciated.

Upon diagonally opposite or alternating 45 ends of the four bolts 3 employed in connection with the splice-bars 1 for connecting two rail-sections together are screwed or applied ratchet-nuts 7, suitably adapted for the convenient application of a wrench thereto. 50 Also applied to each of said bolts are spring dogs or pawls 8, but having their plate-like angular apertured ends 9 receiving diagonally opposite or alternating ends of said bolts for engagement with said ratchet-nuts, 55 and accordingly for the retention of said ratchet-nuts against accidental turning or

unscrewing. The free ends of said pawls or dogs which are caused to have engagement with said ratchet-nuts, are effectively so held by the spring tension of said pawls or dogs. 60 Said pawls or dogs are preferably twisted toward their free or effective ends, thus providing practically for their increased tension or torsional action as they are stressed into initial engagement with said ratchet-nuts. 65 Also inserted upon the bolts 3 between the ratchet-nuts 7 and the splice-bars 1 are washers 10 in order not only to provide a suitable jam or bearing surface for said ratchet-nuts, but also to leave a space between 70 said splice-bars and nuts for a purpose presently seen. Said dogs or pawls are also each provided with a pendent integral lip 11, depending from the inner lateral edge thereof within said space behind the ratchet-nut, to 75 guard against the outward or lateral displacement of said pawls or dogs from any jarring action.

It is therefore apparent from the aforesaid arrangement and construction of parts that 80 in event of the derailment of a car or cars the wheels in leaving the rails could strip the nuts from their bolts upon only one side of the latter, which, however, would still leave the remaining nuts and bolts intact, and consequently 85 the rail-sections connected together, thus preventing their displacement. It is further observed that said invention is exceedingly simple, readily applied, and relatively inexpensive. 90

I claim—

1. In a railway, splice-bars applied to opposite sides of the rail-sections, screw-bolts inserted through said rail-sections and splice-bars and equipped with ratchet-nuts, two 95 such screw-bolts with their nuts being arranged upon each side of the rail-joint, and means of connection between said bolts and nuts, such connection being effected upon each side of each rail-section between a bolt 100 immediately adjacent to the rail-joint and a nut of a successive bolt, said connecting means comprising dogs fixed to diagonally opposite ends of said bolts and engaging correspondingly-arranged nuts of said bolts respectively, for the purpose set forth.

2. In a railway, splice-bars applied to opposite sides of the rail-sections, screw-bolts inserted through said rail-sections and splice-bars and equipped with ratchet-nuts, two 105 such screw-bolts with their nuts being arranged upon each side of the rail-joint, and

- means of connection between said bolts and nuts, such connection being effected upon each side of each rail-section between a bolt immediately adjacent to the rail-joint and a 5 nut of a successive bolt, said connecting means comprising spring-dogs fixed to diagonally opposite ends of said bolts and engaging correspondingly-arranged nuts of said bolts, respectively, said spring-dogs having 10 lateral pendent lips depending intermediately of said splice-bars and said ratchet-nuts, all substantially as and for the purpose set forth.
3. In a railway, the splice-bars applied to 15 opposite sides of the rail-sections, screw-bolts

applied for effective action upon each side of the rail-joints, ratchet-equipped nuts, said nuts being arranged upon diagonally opposite ends of said bolts, and spring dogs or pawls engaging said ratchet-nuts, and each 20 having a depending lateral lip adapted to extend down behind said nuts said spring-dogs having angular apertures receiving corresponding portions of said bolts.

In testimony whereof I affix my signature 25 in presence of two witnesses.

JOSEPH S. BECK.
